PRESSURE MECHANISM

John T. Lancaster, Newton, Mass., assignor to
 United Shoe Machinery Corporation, Flemington, N. J., a corporation of New Jersey

Application October 10, 1945, Serial No. 621,522

24 Claims. (Cl. 1—32)

1

My invention relates to mechanism for applying to work-parts pressure by which they may be held for the performance of an operation upon them. As herein disclosed, the invention is utilized for clamping upon the heel-seat of a shoe a heel to be attached by nailing it through the heel-seat into the heel.

In an operation of the character above indicated, such a work-part as a heel, after having been positioned by the operator, must be retained against both lateral and longitudinal displacement to resist the heavy operating forces applied. An object of the present invention is to effect this retention by simple mechanism which renders the work accessible to the operator and not only applies and holds effectively the clamping pressure, but also enters actively into insuring the correct location of the work. For the attainment of this object, I combine with a frame having a fixed outwardly extending arm, a work-support or jack carried by the frame beneath the arm, upon which arm are three work-clamping abutment devices a portion of which are guided for movement directly in the fixed arm downwardly and inwardly into clamping engagement with the work. In operating upon a heel upon a jacked shoe, these devices engage the peripheral surface of the heel, as at its opposite sides, and the tread-surface. In movement of the devices on the stationary frame-portion, only elements of small mass are necessary, these being readily guided for smooth and easy actuation. The peripheral abutments may be first operated to centralize the work prior to its final clamping, when the tread-abutment engages it. The peripheral abutments are also preferably so organized as to exert a forward locating force, which, when applied to a heel, will seat it against the breast-cut in the shoe-sole. After this positioning action, the tread-abutment becomes active to exert, with its companions, the final clamping action. The abutment devices, regardless of their particular application, are preferably in the form of spindles guided upon the frame and provided with threads engaged by nuts. The nuts are shown as provided with external gear-teeth, which, through trains of gearing, are rotated by connection to a slide or other actuating member. The pitch of the co-operating screw-threads is such that the spindles are locked against retraction through reaction of the pressure applied to the work. To obtain the correctly timed movement of the work-clamping devices, a lock is provided for the tread-abutment, when a heel is being operated upon, which lock may act on the abutment-gearing. After the side

2

abutments have attained the desired relation to the work, to permit operation of the tread-abutment the lock is released upon movement of the actuating member, as by means movable with the gearing for the side abutments. When all the abutments have engaged the work, a balanced pressure is preferably applied. This may be effected through an equal-arm-lever fulcrumed upon the actuating member or slide and connected at its ends to two trains of gearing. For inclusion in such machines as those by which heels are attached, the abutment device which engages the tread-surface of the heel is adjustable so the axis of its spindle may be normal to said surface. This spindle herein appears as operating through a support guided along a curved path, there being means arranged to vary the position of the support and thus the inclination of the spindle.

In the accompanying drawings, illustrating one of the several possible embodiments of this invention,

Fig. 1 is a front elevation of the upper portion of a heel-attaching machine, including my improved pressure mechanism;

Fig. 2, a side elevation thereof;

Fig. 3, a rear elevation of the abutment-operating mechanism;

Figs. 4 and 5 are horizontal sections on the lines IV—IV and V—V, respectively, of Fig. 3;

Fig. 6 is a sectional detail of a portion of the gearing for the side abutments;

Fig. 7, a detail top plan view of the side abutment members in engagement with a heel;

Fig. 8 is a rear elevation, showing the position of the parts at the instant when the tread mechanism is to become effective to lower the tread abutment; and

Fig. 9 is a rear elevation showing the position of the parts when both the side and tread abutments have become effective to clamp the heel and the pressure between them has been equalized.

The machine in connection with which I have chosen to disclose my invention is of the general character of that made the subject of Letters Patent of the United States No. 1,545,575, Standish, July 14, 1925. This has a vertical column 10, at the front of which is a support or jack 12 having reciprocating in its vertical passages drivers 14 to insert nails N, which they carry, through the heel-seat of a jacked shoe s, into an applied heel h clamped in place to resist the nail-inserting thrust of the drivers by the holdown of the present invention.

Extending forward from the top of the column

is a fixed arm A having a rear wall 16, spaced vertical side walls 18, 18 and a horizontal top wall 20. At the lower forward portion of each side wall are inwardly inclined extensions 22, from each of which project spaced arms 24, 24 serving as guides for downwardly and inwardly inclined abutment devices S, S for engagement with the periphery of the heel at the sides and rear. Located midway between and in front of the arm-extensions 22 is a forwardly and downwardly curved extension 26, 10 in which is guided for angular adjustment a support 28 for an abutment device T, for engagement with the tread-surface of the heel. This adjustment permits the device T to move into clamping engagement with all heels along lines normal to their tread-surfaces. The form of the side walls of the heels is such that effective engagement of the abutments S may be had without adjustment.

As to the adjustment of the abutment device T, the arm-extension 26 has opposite curved ways 30, 30, in which a correspondingly curved portion of the support 28 is guided. The curve of the ways is along an arc the center of which lies in the heel-seat of a jacked shoe, so the angular adjustment of the abutment T will present it in a direction substantially correct for all heels. The upper portion of the support 28 is in the form of a closed loop having upper and lower walls 32, 32 and opposite side walls 34, 34. At the rear, the walls 34 are connected by a bridge-piece 36 in which is a slot 38. Extending horizontally through the slot is a shaft 40 journaled in the spaced side walls of an adjusting traveler 42, one side of the top of which is threaded to receive a horizontal screw 44 rotatable in bearings 46, 46 on the wall 20 of the arm A. When the screw is rotated through a hand-wheel 48 on its forward extremity, the resulting movement of the traveler 42 is communicated to the support 28 through the engagement of the shaft 40 with the wall of the slot 38. The support is thus shifted forwardly or rearwardly along the curved ways 30 of the arm-extension 26, and thus angularly, to establish the desired relation of the device T to the tread-surface of the heel h. This device is shown herein as consisting of a spindle 50 guided for axial movement through the walls 32, 32 of the support 28. The spindle has at its lower extremity an enlargement 52, the surface 54 of which is, by the adjustment just described, brought into parallelism with the tread-surface of the heel to be attached. The spindle 50 is splined into the walls 32 for longitudinal reciprocation without rotation, and is externally threaded to receive a nut 56 rotatable between said walls, there being shown a thrust-bearing 58 interposed between the nut and the upper wall. On its periphery the nut has the teeth of a spiral pinion, with which meshes a spiral pinion 60 fixed to the shaft 40. The latter pinion meshes with a spiral gear 62 fast upon the forward extremity of a horizontal shaft 64 rotatable in the traveler 42 and extending rearwardly through a bearing 66 depending from the wall 20. A thrust-bearing 68 is shown as interposed between the shaft and the rear wall of the traveler. Splined upon the rear of the shaft, between the bearing 66 and the wall 16, is a pinion 70 which is driven through a train of gearing rotatable upon the wall 16. This train includes successively (Figs. 3 and 4) a gear 72, a pinion 74 turning with the gear, and gear-segments 76 and 78 rotatable together, the last of these meshing with a vertical rack 80 guided to reciprocate at one side of the column 10. The

means for actuating this rack, to rotate the nut 56 and thereby reciprocate the spindle 50, will be described in connection with the related operation of the side abutments S.

Each of the abutment devices S has a spindle 82 guided in one of the pairs of support-arms 24, 24, so it may be moved longitudinally in a downwardly and inwardly inclined direction toward the heel h upon the jacked shoe s. Upon the lower end of each spindle is pivoted at 84 a heel-engaging abutment member 86, provided with a yieldable covering or pad 88. A leaf-spring 89, secured to the spindle and bearing against the member, holds this in, so it may adapt itself yieldingly to the curvature of the particular heel being operated upon. The form of the member 86 and the yieldability of its padding allow it to extend somewhat over the rear of the heel (Fig. 7), so it may not only prevent rearward displacement but also may apply some forward pressure during the descent of the abutment devices. Each spindle 82 is splined into its guiding pair of arms 24, and has formed upon it an external thread received in a nut 90 seated between the arms. Bearings 91 about the spindles may receive the upward thrust of the nuts. Similarly to the nut 56 of the tread-abutment device, each of the nuts 90 has external spiral gear-teeth, with which meshes a spiral pinion 92 secured to a short shaft 94 (Fig. 6) journaled in a portion of one of the wall-extensions 22. Fixed to the end of each shaft 94 opposite the spiral pinion is a bevel-pinion 96, meshing with a bevel-gear 98 fixed to a short shaft 100 journaled in the wall 16 and having attached to its rear extremity a pinion 102. The gear 98 is common to both abutment devices S, S. The pinion 102 is rotated through a series of gears comprising a gear 104 (Figs. 3 and 5) having turning with it a pinion 106, meshing with a gear-segment 108, with which turns a gear-segment 110 meshing with a vertical reciprocatory rack 112 guided in the column 10 at the side opposite the rack 80. By its movement, the rack 112 rotates the nuts 90 and reciprocates the spindles 82.

Means is provided to draw down successively, through the interposed gearing just described, the racks 112 and 80 to first bring abutment devices S, S into engagement with the sides and rear of the heel upon the heel-seat of the jacked shoe, and then the abutment T against the tread-surface of said heel. In the column below the racks is guided a slide 114, which may be lowered through a link 116 upon the depression of the customary treadle, this being held normally raised by its spring. The treadle and spring are not illustrated. At the top of the slide is fulcrumed an equal-arm lever 118 (Fig. 3), the opposite extremities of which are joined to the racks by links 120, 120. Movable through the side rack 89 is a locking plunger 122, urged in by an expansion-spring 124 so its outer end tends to be withdrawn from a contact-lever 126 fulcrumed upon the column. The upper contact-end of the lever is held yieldably toward the latch by an expansion-spring 128, its normal position being adjustably determined by a rod 130 pivoted to it and threaded to receive a nut 132 contacting with the outside of the column. When the heel-abutments are raised from the work to their inactive positions the parts are as shown in Fig. 3. The plunger 122 is held out, acting against the force of the spring 128 and with its end above that of the lever 126, by a controlling slide 134 guided to shift horizontally in a fixed portion 136 of the wall 16. The

slide 134 has at its opposite ends depending arms 138, 140. The arm 138 initially, with the slide 114 raised, received the contact, near its lower extremity, of a roll 142 rotatable upon the inner end of the plunger 122. The opposite arm 140 is thrust, by the action of the plunger-spring 124, against a roll 144 rotatable upon the rack 112 at a higher level than the roll 142. With the elements thus related, upon depression of the slide 114 by the link 116, the tread-rack 80 is locked against downward movement by the engagement of the plunger with the end of the lever 126, while the side rack 112 is free to move. Consequently, the left-hand end of the lever 118 (Fig. 3) temporarily becomes the fulcrum, and the opposite end of the lever is lowered and draws down the rack 112. Through the interposed gearing, the nuts 90, 90 are rotated and the spindles 82, 82 depressed to carry the abutment-members 86, 86 toward the opposite sides and rear of the heel. When these abutment-members have reached points at or in proximity to the heel, the rack 112, and therefore the roll 144, will have been so lowered that the roll leaves the arm 140 of the lock-controlling slide 134 (Fig. 8). This is thereby freed for movement to the right, produced by the plunger-spring 124, which at the same time removes the end of the plunger from the contact-lever 126. Now the tread-rack 80 is released, and continued depression of the slide 114 lowers this rack (Fig. 9), and, through the interposed gearing, rotates the nut 56 to carry down the spindle 50 so its surface 54 engages the tread-surface of the heel. With all the heel-abutments thus made effective, their clamping force is balanced through the lever 118 for whatever further pressure may be applied to the treadle. They will, therefore, act uniformly to retain the heel on the heel-seat of the jacked shoe against the displace effect of nail-insertion by the drivers 14. On account of the angles of the threads on the spindles and their actuating nuts, this driving force cannot cause the spindles to rotate the nuts and all three abutments are locked in engagement with the heel. Consequently, the force cannot be transmitted back through the treadle to the foot of the operator and no other lock for the holdown is required. When the treadle is released by the operator and its spring lifts the slide 114, both racks are raised by the links 120. The roll 144 on the rack 112 first reaches an inclined end-surface 146 on the slide-arm 140, shifting the slide 134 to the left and holding it by contact with the vertical outer surface of the arm 140. When the roll 142 of the plunger 122 arrives at the inclined end 146 of the opposite slide-arm 138, the plunger is forced out, the spring 124 being compressed, and is retained by the outer vertical surface of the arm. The outer end of the plunger travels briefly along the inner side of the lever 126, the spring 128 yielding. Finally, the end of the plunger reaches a level above the end of the lever and the spring 128 urges this into its rack-retaining position (Fig. 3). During the ascent of the slide 114 and the racks 80 and 112, the nuts 56 and 90 were being rotated through the gearing to raise the spindles 50 and 82 simultaneously, the elements thereby being restored to their normal relation.

In the use of a heelng machine having the holdown of this invention, the operator, by turning the hand-wheel 48, may adjust the angle of the tread-abutment-spindle 50 so it is normal to the tread-surface of the line of heels to be operated upon. He delivers a load of nails N to

the driver-passages of the jack 12, places a shoe s upon the jack 12 and applies a heel h to its heel-seat in approximately the correct position. The side abutments S, S and the tread-abutment T are at this time fully raised and substantially removed from the work to give ample room for the free introduction of the heel between them and its arrangement upon the heel-seat. With the heel still held by the operator, the treadle is depressed, so the link 116 draws down the slide 114, the actuating rack 80 for the tread-abutment device T being locked to the column 10 by the plunger 122 and contact-lever 126. The lever 118 upon the slide fulcrums upon the link 120 of the rack 80, causing the opposite link to draw down the rack 112 associated with the side abutments, and the lowering of their threaded spindles 82 by rotation of the nuts 90 geared to the rack. The tread-abutment remains at rest. As the side members 86 approach the heel, moving inwardly at the same rate, they position it transversely of the heel-seat. At the same time, the curved portions of the members may thrust it forward sufficiently to insure that the breast-edge is seated against the breast-cut in the sole of the shoe. During this action of the side abutments, the tread-abutment will remain raised and at rest, so the operator may, without interference, retain his grasp upon the heel until it has been fully centered. The roll 144 upon the rack 112 will now have permitted the controlling slide 134 to release the rack 80 from the plunger 122, so the lever 118 will draw down said rack 80 and rotate the nut 56 which is geared to it, thereby lowering the threaded tread-spindle 50. When the tread-engaging surface 54 of this spindle contacts with the tread-surface of the heel h, the side abutments will have completed the positioning of the heel, and the tread-abutment will apply thereto clamping pressure in the direction of its longitudinal axis and both hold it back against the rear portions of the side members and clamp it firmly upon the heel-seat of the shoe. The force exerted upon the heel by all the abutment devices will be balanced by the equal-arm-lever 118. The magnitudes of the side and tread-clamping forces will be determined by the design of the actuating gearing, the former preferably being the greater. The clutch of the heelng is tripped as usual during final depression of the treadle, to cause the driving from the jack 12 of the heel-attaching nails N. After the insertion of the nails, the operator releases the treadle; the slide 114 is lifted by the treadle-spring; the nuts 90 and 56 are rotated by their gearing reversely to the direction during treadle-depression; and the plunger 122 again locks the tread-rack 80 to the frame. The abutments S, S and T have been withdrawn from the work and the lowered shoe may be removed from the jack. The machine is now ready for the succeeding operation.

It will be seen that the locking of the abutment-members is positive and not subject to the variations produced by slipping clutch devices. There is no heavy clamping head to raise, and all the play in the mounting of said head is eliminated. The side abutments, acting upon the heel before the tread-abutment, centralize the heel more accurately than does the usual rear fork and carry it against the breast-cut of the shoe-sole. Further, by their location and direction of applied pressure, they tend to resist the lateral splitting of the heels. The tread-abutment exerts its force in a direction normal to the tread-surfaces of heels of all forms, to apply the clamping force to

the best advantage. This tread-abutment when raised is high enough above the shoe on the jack to give the operator ample room to manipulate and inspect the work.

Having thus described my invention, what I claim as new and desire to secure by Letters Patent of the United States is:

1. In combination, a frame including a fixed outwardly extending arm, a work-support carried by the frame beneath the arm, three work-clamping devices movable upon the arm downwardly and inwardly toward the work-support, a portion of said devices being guided for movement directly in the fixed arm, and means for moving the devices into clamping engagement with work on the support.

2. In combination, a frame including a fixed outwardly extending arm, a work-support carried by the frame beneath the arm, there being formed in the arm at each side a downwardly and inwardly inclined guide, a front guide movable upon the arm, means arranged to change the inclination of the front guide and to retain it against movement, three work-clamping devices movable in the guides toward and from the work-support, and means for moving the devices into clamping engagement with work on the support.

3. In combination, a frame including a fixed outwardly extending arm with spaced side walls and a forward extension from said walls, there being downwardly and inwardly inclined guides in the side walls and a downwardly and outwardly curved guideway in the extension, a work-support carried by the frame beneath the arm, work-clamping devices movable in said guides toward and from the work-support, a support movable in the extension-guideway, means arranged to move said support along the guideway, a work-clamping device movable in the guideway support, and means for moving the devices into clamping engagement with work on the support.

4. In combination, a frame including a fixed outwardly extending arm with spaced side walls and a forward extension from said walls, there being downwardly and inwardly inclined guides in the side walls and a downwardly and outwardly curved guideway in the extension, a work-support carried by the frame beneath the arm, work-clamping devices movable in said guides toward and from the work-support, a support movable in the extension-guideway, a member movable upon the frame and engaging the support to move it in the guideway, means arranged to move the member, a work-clamping device movable in the guideway-support, and means for moving the devices into clamping engagement with work on the support.

5. In combination, a frame, an arm extending outwardly therefrom, a work-support beneath the arm, threaded spindles guided at opposite sides of the arm and at the front, they being provided with work-engaging portions, nuts upon the spindle-threads and rotatable upon the arm, and means for rotating the nuts and thereby actuating the spindles.

6. In combination, a frame, an arm extending outwardly therefrom, a work-support beneath the arm, threaded spindles guided at opposite sides of the arm and at the front, they being provided with work-engaging portions, nuts upon the spindle-threads and rotatable upon the arm, an actuating member movable upon the frame,

and gearing connecting the actuating member to all the nuts to effect their rotation.

7. In combination, a frame, an arm extending outwardly therefrom, a work-support beneath the arm, threaded spindles guided at opposite sides of the arm and at the front, they being provided with work-engaging portions, nuts upon the spindle-threads, they being rotatable upon the arm and provided with external gear-teeth, a slide movable upon the frame, and trains of gearing connected to the slide and having elements meshing with the teeth upon the nuts.

8. In combination, a frame, an arm extending outwardly therefrom, a work-support beneath the arm, threaded spindles guided at opposite sides of the arm and at the front, they being provided with work-engaging portions, nuts upon the spindle-threads and rotatable upon the arm, an actuating member movable upon the frame, and gearing connecting the actuating member to all the nuts to effect their rotation, an element of the gearing being common to the nuts of both side spindles.

9. In combination, a frame, an arm extending outwardly therefrom, a work-support beneath the arm, threaded spindles guided at opposite sides of the arm and at the front, they being provided with work-engaging portions, nuts upon the spindle-threads and rotatable upon the arm, an actuating member movable upon the frame, and means for communicating the movement of the actuating member first to the side spindles and then to the front spindle.

10. In combination, a frame, an arm extending outwardly therefrom, a work-support beneath the arm, threaded spindles guided at opposite sides of the arm and at the front, they being provided with work-engaging portions, nuts upon the spindle-threads, they being rotatable upon the arm and provided with external gear-teeth, a slide movable upon the frame, trains of gearing connected to the slide and having elements meshing with the teeth upon the nuts, and means for locking one of the trains of gearing and thereby the corresponding spindle.

11. In combination, a frame, an arm extending outwardly therefrom, a work-support beneath the arm, threaded spindles guided at opposite sides of the arm and at the front, they being provided with work-engaging portions, nuts upon the spindle-threads, they being rotatable upon the arm and provided with external gear-teeth, a slide movable upon the frame, trains of gearing connected to the slide and having elements meshing with the teeth upon the nuts, means for locking one of the trains of gearing and thereby the corresponding spindle, and means controlled by the other train of gearing for releasing the locking means.

12. The combination with a work-support, of movable work-clamping devices co-operating with the support, trains of gearing through which the devices are moved, a movable actuating member connected to elements of the trains of gearing, means for locking an element of one of the trains and thereby the corresponding work-clamping device, a controlling member for the locking means, and means activated by the actuating member for operating the controlling member.

13. The combination with a work-support, of movable work-clamping devices co-operating with the support, trains of gearing, each including a rack and through which the devices are moved,

an actuating slide, a lever fulcrumed upon the slide and connected to the racks, means for locking one of the racks and thereby the corresponding work-clamping device, a second slide movable in opposite directions between the racks to set and release the locking means, and means associated with the activating slide for operating said second slide, to set said locking means.

14. The combination with a work-support, of movable work-clamping devices co-operating with the support, trains of gearing, each including a rack through which the devices are moved, an actuating slide, a lever fulcrumed upon the slide and connected to the racks of both trains, a plunger by which one of the racks is locked, and a controlling slide for the plunger movable during movement of the actuating slide in one direction to apply the lock and thereby secure certain of the work clamping devices and movable by the plunger during movement of the actuating slide in the opposite direction to release the lock and thereby said work-clamping devices.

15. The combination with a work-support, of work-clamping devices co-operating with the support, trains of gearing, each including a rack and through which the devices are moved, an actuating slide, a lever fulcrumed upon the slide and connected to the racks, co-operating locking members for certain of the work-clamping devices, one member being movable upon one of the racks into and out of locking position and the other member being yieldable upon a fixed support, and a controlling member for moving the rack-borne locking member into locking position during movement of the actuating slide, the other locking member yielding in response to such movement of the rack-borne member.

16. In a heel-attaching machine, the combination with a frame, of a jack carried thereby, said frame having a fixed portion extending above the jack, opposite abutment devices guided for longitudinal movement only in the fixed frame-portion into clamping engagement with the opposite sides of a jacked heel, a guide variable in position upon the fixed frame-portion, an abutment device movable in the variable guide for engagement with the tread-surface of the heel, and means for moving the abutment devices.

17. In a heel-attaching machine, the combination with a frame, of a jack carried thereby, a threaded spindle guided in the frame at each side of the jack and provided with an abutment for engagement with the side of a heel upon a jacked shoe, a threaded spindle guided upon the frame and provided with an abutment for engagement with the tread-surface of the heel, a nut rotatable in the frame about each spindle, and means for rotating the nuts to reciprocate the abutments into and out of engagement with the heel.

18. In a heel-attaching machine, the combination with a frame, of a jack carried thereby, a threaded spindle guided in the frame at each side of the jack and provided with an abutment for engagement with the side of a heel upon a jacked shoe, a support guided in the frame along a curved path having its center at substantially the heel-seat of the jacked shoe, a threaded spindle guided in the support and provided with an abutment for engagement with the tread-surface of the heel, means arranged to move the support, nuts rotatable about the spindles in the

frame and support, and means for rotating the nuts.

19. In a heel-attaching machine, the combination with a frame, of a jack carried thereby, a threaded spindle guided in the frame at each side of the jack and provided with an abutment for engagement with the side of a heel upon a jacked shoe, a support guided in the frame along a curved path having its center at substantially the heel-seat of the jacked shoe, a threaded spindle guided in the support and provided with an abutment for engagement with the tread-surface of the heel, a screw rotatable upon the frame, a traveler movable upon the frame, it being threaded upon the screw and engaging the support to shift it along its guide, means arranged to move the support, nuts rotatable about the spindles in the frame and support, and means for rotating the nuts.

20. In a heel-attaching machine, the combination with a frame, of a jack carried thereby, a threaded spindle guided in the frame at each side of the jack and provided with an abutment for engagement with the side of a heel upon a jacked shoe, a support guided in the frame along a curved path having its center at substantially the heel-seat of a jacked shoe, a threaded spindle guided in the support and provided with an abutment for engagement with the tread-surface of the heel, a screw rotatable upon the frame, a traveler movable upon the frame, it being threaded upon the screw and engaging the support to shift it along its guide, nuts rotatable about the spindles in the frame and support, a shaft rotatable in the frame and along which the traveler is movable, gearing connecting the shaft to the nut of the tread-spindle, gearing through which the nuts of the side spindles are rotated, and means for driving the gearing.

21. In a heel-attaching machine, a jack, an abutment device for engagement with the peripheral surface of a heel upon the heel-seat of a jacked shoe, an abutment device for engagement with the tread-surface of the heel, means for first causing movement of the abutment device into engagement with the peripheral heel-surface, then causing movement of the abutment device into engagement with the tread-surface and finally exerting upon the heel a balanced pressure by the abutments, and co-operating threaded members through which the movement of the peripheral and tread-abutment devices is produced.

22. In a heel-attaching machine, a jack, an abutment device for engagement with the peripheral surface of a heel upon the heel-seat of a jacked shoe, an abutment device for engagement with the tread-surface of the heel, gearing through which the peripheral abutment device may be moved, gearing through which the tread-abutment device may be moved, a movable member, an equal-arm-lever fulcrumed upon the member and connected at its opposite ends to the gearing for the respective abutments, and means for moving the member and thereby the abutment devices.

23. In a heel-attaching machine, a jack, an abutment device for engagement with the peripheral surface of a heel upon the heel-seat of a jacked shoe, an abutment device for engagement with the tread-surface of the heel, gearing through which the peripheral abutment device may be moved, gearing through which the tread-abutment device may be moved, a movable ac-

sliding member for the abutments, means for moving the member and thereby the abutments, and means for locking the tread-abutment against movement until the peripheral abutment has approached the heel.

24. In a heel-attaching machine, a jack, an abutment device for engagement with the peripheral surface of a heel upon the heel-seat of a jacked shoe, an abutment device for engagement with the tread-surface of the heel, means for first causing movement of the abutment device into engagement with the peripheral heel-surface and then causing movement of the abutment device into engagement with the tread-surface, means for locking the tread-abutment device .10

5

against movement, and means controlled during the movement of the peripheral abutment device for releasing the lock.

JOHN T. LANCASTER.
